UNITED STATES PATENT OFFICE.

EUGENE POWELL, OF COLUMBUS, OHIO.

RAIL-TIE.

SPECIFICATION forming part of Letters Patent No. 790,658, dated May 23, 1905.

Application filed January 17, 1905. Serial No. 241,419.

To all whom it may concern:

Be it known that I, EUGENE POWELL, a citizen of the United States, and a resident of Columbus, in the county of Franklin and State 5 of Ohio, have invented a new and Improved Rail-Tie, of which the following is a full, clear, and exact description.

My invention relates to an improvement in rail-ties formed of concrete or other plastic 10 material.

The principal objects of the invention are to provide means secured in the tie for effectively holding the rail, for preventing the swinging of the rail on the tie, or vice versa, for strengthening the tie, and at the same time for permitting the tie to be readily placed in the road-bed.

Further objects of the invention will appear in the course of the subjoined description.

Reference is to be had to the accompanying drawings, forming a part of this specification, in which similar characters of reference indicate corresponding parts in all the figures.

Figure 1 is a perspective view showing a portion of a pair of rails and a tie embodying a preferred form of my invention. Fig. 2 is a plan view thereof, partly broken away, and one rail being removed. Fig. 3 is a sectional view on the line 3 3 of Fig. 2. Fig. 4 is a sectional view similar to Fig. 3 of another form of my invention, and Fig. 5 is a sectional view on the line 5 5 of Fig. 4.

The tie 10 is formed of concrete or other 35 plastic material, with a pair of slots or depressions 11 on the upper surface. These slots extend across the tie and are preferably of a depth equal to the depth of the edge of the flange of the rail to be used with the tie.

They are also of a width equal to the width 40 of the flange of the rail, and it is intended that the rail shall seat in these depressions. It will be seen that by this construction the sluing of the tie and spreading of the rails 45 are prevented and the two parts are effectively secured together against any angular or other motion with respect to each other.

The tie is preferably provided with a plurality of strengthening-bars 12, embedded in 50 the tie in the act of molding and located with

their upper surfaces at the bottom of the depression 11. These strengthening-bars preferably have bent ends 13 for more securely holding them in position. It will be readily understood that they can be applied to the 55 tie at other distances from the surface than that shown.

Located under each of the depressions 11 is a stirrup 14, provided with inwardly-projecting feet 15 in the lower part of the tie. The 60 top of each stirrup is located on the plane of of the top of the tie and has a depression 16 extending to the bottom of the depression 11. When the rails are applied to the ties, they will rest in the depressions in the ties and stirrups 65 and also, preferably, on the upper surfaces of the strengthening-bars. The stirrups are provided with perforations, through which bolts or screws 17 pass into the tie. The bolts can be threaded into the stirrups, or nuts 17^a can 70 be embedded in the concrete for their reception. These bolts are designed for holding clamps 18. The clamps are located with their lower surfaces upon the top of the tie and stirrup and also bearing upon the top of 75 the flange of the rail. The bolts pass through the clamps and in an obvious manner secure them to the stirrups. The depressions 11 are provided with notches 19 for receiving the stirrups. Eyes 20 are provided for assisting in 80 manipulating the tie and putting it into or out of place.

In the form shown in Figs. 4 and 5 the stirrup 14^a has outwardly-projecting feet 15^a and is sunk below the surface of the tie through- 85 out. The clamps 18^a have only one bolt 17 and rest on the top of the tie. The other parts are the same as shown in the preceding views.

It will be seen that the rails are securely 90 clamped in position on the stirrups and that they are effectively held against motion in all directions; also, that the tie is strong and unyielding in nature, although the rails can be readily loosened from it and the tie with- 95 drawn from the road-bed without presenting any obstruction to its removal. It will be observed also that the weight applied to the rail will be transmitted through the stirrup in two directions and will be supported by 100

the under side of the top of the stirrup and also by the feet, so that the area which supports the weight will be greatly increased by my invention. Furthermore, the entire weight 5 of the rail is not supported by the stirrup, for it bears upon the concrete and tie-rods 12 upon both sides of the stirrup.

The stirrups and strengthening- rods are 10 preferably formed of wrought- iron; but it will be understood that my invention is not limited to this material. The tie is molded in any desired manner; but I prefer to place the flask face downward with a bottom board. Across the bottom board, at the points where 15 the rail-seats are to be located, a thin block or pattern is placed. The stirrups are then inserted and the concrete or other plastic material poured in and tamped in the usual way.

While I have illustrated and described preferred forms of my invention, it will be readily understood that it is capable of embodiment in many other forms and that it is not limited to those shown.

Having thus described my invention, I claim 25 as new and desire to secure by Letters Patent—

1. A rail-tie composed in the main of plastic material and having a stirrup embedded therein in the stirrup having an upper surface located below the upper surface of the tie for the reception of the lower surface of a rail, a pair 30 of clamps adapted to rest upon the top of the tie and on the top of the flange of the rail, and means for securing each clamp to the stirrup.

2. A rail-tie composed in the main of plastic material and having a depression across the 35 face thereof equal in depth to the depth of a flange of a rail to be applied to the tie, and having a stirrup embedded therein, an upper surface of the stirrup being located flush with the lower surface of said depression.

3. A rail-tie composed in the main of plastic material and having a depression across the 40 face thereof equal in depth to the width of a flange of a rail to be applied to the tie and having a stirrup embedded therein, an upper

surface of the stirrup being located flush with the lower surface of said depression, a pair of clamps adapted to rest on the top of the tie on each side of a rail and on the top of the flange of the rail, and means for securing each 50 clamp to the stirrup.

4. A rail-tie composed in the main of plastic material and having a depression across the face thereof equal in depth to the width of a flange of a rail to be applied to the tie and having a stirrup embedded therein, part of the upper surface of the stirrup being located flush with the upper surface of the tie and having a depression located flush with the lower surface of said depression in the tie, a 60 pair of clamps adapted to rest on the top of the tie and stirrup on each side of a rail and on the top of the flange of the rail, means for securing each clamp to the stirrup, and a plurality of longitudinal strengthening-bars 65 embedded in the material of the tie, their upper surfaces being in the same plane as the top of said stirrup.

5. A rail-tie composed in the main of plastic material, having a pair of depressions across 70 its top, each being of the width and depth of the flange of a rail and being located the same distance apart as the two rails of the track, a stirrup longitudinally embedded in the tie under each of these depressions and each having 75 a portion of its upper surface coincident with the lower surface of one of the depressions, the depressions being provided with notches extending outwardly to receive the stirrups, a pair of clamps for each stirrup, said clamps 80 resting on the top of the tie and on the flanges of the rails, and a bolt for each clamp passing through the clamp.

In testimony whereof I have signed my name to this specification in the presence of two sub- 85 scribing witnesses.

EUGENE POWELL.
